UNITED STATES PATENT OFFICE.

HERBERT H. BUFFUM, OF THE WEIRS, NEW HAMPSHIRE, ASSIGNOR OF ONE-THIRD TO
ROBERT M. PIERSON, OF AKRON, OHIO.

CARBURETER.

1,202,025.

Specification of Letters Patent. Patented Oct. 24, 1916.

Application filed December 11, 1913. Serial No. 805,880.

To all whom it may concern:

Be it known that I, HERBERT H. BUFFUM, a citizen of the United States, residing at The Weirs, in the county of Belknap and 5 State of New Hampshire, have invented certain new and useful Improvements in Carbureters, of which the following is a specification.

This invention, which relates to carbureters employing a throat tube of variable 10 diameter or other means for varying the effective aperture of the air throat in the aspirator, has for one of its objects the provision of a simple and effective tube-operating means adapted to permit the free 15 passage of mixture through the tube and its connections.

A second object is to furnish means for coöordinating the structure and operation of 20 the throttle valve and the tube-actuating devices, such means being preferably of such a nature that the tube may, if desired, be expanded and contracted independently of the throttle movements, thus allowing the 25 mixture to be enriched above the normal at certain times such as in starting the motor when cold, or to obtain the increased pulling power which results from a slow-burning mixture, or on the other hand to allow 30 the proportion of air to be increased at other times for the sake of fuel economy.

A further object of the invention is to provide the carbureter with a type of throat tube which will allow as near an approximation 35 to the true Venturi tube as is consistent with durability and a desired degree of fluid-tightness of a collapsible tube.

Other incidental objects obtained by my 40 invention will appear from the succeeding description and claims.

Of the accompanying drawings, Figure 1 represents a vertical section of a carbureter constructed according to my invention, with the collapsible tube shown in its expanded 45 condition. Fig. 2 represents a similar view with the tube contracted. Fig. 2^a represents a cross section of the tube and its casing, taken above the fuel nozzle. Fig. 3 represents a side elevation of the upper part of 50 the carbureter. Fig. 4 represents a section at right-angles to Fig. 3. Fig. 5 represents a top plan view with the throttle valve partly broken away. Fig. 6 represents a plan view showing a form of foot-controlled

operating-connections which may be employed. Fig. 7 represents a horizontal section, and Fig. 8 a side elevation, showing a modified embodiment.

Referring at first to Figs. 1 to 6 inclusive, 10 is a vertical tubular casing having an air-inlet 11 at its lower end, spanned by a bridge 12 which supports the fuel jet-nozzle 13, the said bridge and nozzle containing the fuel-duct 14 which leads from an ordinary float-chamber or reservoir 15. In 15 order to obtain the greatest efficiency from the collapsible air-tube which I employ, I prefer to employ a fuel-jet nozzle 13 of considerable relative diameter at its outlet end, and to spread the issuing jet of fuel in an 20 expanded column or sheet of spray and vapor which will fully utilize the increased suction and atomizing effect which I obtain through the employment of such a tube. It will be noted that the jet-outlet 16 is formed 25 in a thin partition 17 and is given an annular form by the conical end or point of a fixed rod 18 supported from below the jet-nozzle and occupying the middle of the latter. This particular structure tends to project the issuing fuel in a conical sheet or spray into the passing air current, and the effect is enhanced by means of an external spreader member 19 mounted above the jet orifice and having a conical lower end, this 30 spreader being mounted in a ring 20 connected by bridges 21 with the body of the nozzle and preferably having a threaded connection 22 therewith which permits the spreader to be used as a valve for adjusting 35 the effective size of the jet outlet. I do not, however, limit myself to this exact construction. One of the important features is to allow considerable expansion or spreading, and some vaporization of the issuing fuel 40 spray before it encounters the air current, and to provide for positively controlling the effective aperture of the air-throat in the aspirator at the mixing point, as by means of the flexible-walled tube herein described. 45 In other words, there is, as will be evident, an expansion chamber or chambers of considerable capacity interposed between the relatively-small fuel orifice 16 and the air 50 passage surrounding the final outlet of nozzle 13, the said chamber in this instance being formed between the nozzle wall 17, the spreader 19 and the ring and bridges 20, 21.

Such chamber may be made of any suitable depth and capacity, and I find that its presence results in a marked economy in the amount of fuel consumed.

5 While I am aware that fuel spreaders are not broadly new, it is to be noted that the positive control of the air velocity at the mixing point, as attained by my flexible-walled tube, enables the operator to control at will the pulling power of the air-current exerted through said expansion chamber, and to adjust this power to different atmospheric and motor conditions.

23 is the collapsible air-tube, preferably 15 having a construction similar to that described in my Patent No. 1,108,128, dated August 25, 1914, being composed of thin longitudinal plates or slots 24 which overlap as shown in Fig. 2^a, their ends being 20 anchored in lower and upper rings 25, 26. The lower ring abuts against a shoulder 27 near the bottom of the casing 10, and the upper ring is slidable in said casing toward and from the lower ring.

25 For the purpose of sliding the upper ring 26, I have shown a follower ring 28 mounted to slide in an upper casing or tube-section 29 which is connected with the casing 10 by a screw-threaded coupling or union 30, the 30 said coupling allowing the two parts of the casing to be separated at a point which affords convenient access to the interior parts, and also permitting the upper section 29 to be turned at different angles so as to 35 accommodate its attaching flange 31 to the position of the complementary flange on the engine-pipe. Turning of the follower ring is prevented by a spline connection formed by a pin 32 in the side wall of the casing- 40 section 29, and a longitudinal groove 33 formed in the ring.

The follower ring 28 is provided with a cross-pin 34 on the middle part of which is mounted to turn a roller 35, and this roller 45 is engaged by the edge of a cam 36 secured to a rock-shaft 37 which is mounted in bearings in the casing-section 29. To the outer end of the rock-shaft is pinned an operating lever or arm 39. Preferably the rock-shaft 50 37 is, as shown, co-axial with a butterfly throttle-valve 40 which controls the effective size of the mixture-passage, the said valve having two hub-members loosely journaled on shaft 37 on opposite sides of the hub of 55 cam 36, as best seen in Figs. 4 and 5. The cam occupies a diametric slot 41 formed in the throttle valve, which is of such length as to permit movements of the cam independently of the valve, and also provides a 60 certain minimum opening for the passage of the mixture when the throttle valve is completely closed as shown in Fig. 2. To operate the throttle valve I provide an external arm or lever 42 attached to a sleeve 43 65 loosely journaled in the casing-section 29

and on the rock-shaft 37, and formed on its inner end with a pair of jaws 44 which embrace between them one edge of the valve-disk 40. 45 is an adjustable stop for either or both of the arms 39, 42.

Fig. 1 represents substantially the normal shape which the tube 23 tends to assume when not under axial compression, its form being then substantially though not quite cylindrical; that is the plates will be very 70 slightly concaved by the small permanent set which they retain after once having been bowed inwardly. On turning the rock-shaft 75 37 clockwise from the position shown in Fig. 1, the follower ring 28 is, by the action of cam 36 on its roller 35, pushed downwardly, and thereby the ring 26 is depressed and the plates forming the tube 23 are caused to bow inwardly and produce a contraction or waist in the intermediate portion of the tube surrounding the outlet of the jet-nozzle 13. In this way an air-throat of 80 85 variable diameter is formed around the nozzle.

While the tube 23, as shown in Fig. 2, does 90 not assume the exact shape of the theoretical venturi, it gives a nearer approximation thereto than I believe has heretofore been afforded by any practical form of collapsible tube. The longitudinal collapsing pressure 95 may, as shown, be realized by simple operating connections, and the plates or slats of the tube may be caused to act as bow-springs which return the tube to its normal diameter when pressure is relieved.

The drawings represent three modes of co-ordinating the movements of the throttle and tube. The cam 36 and throttle-valve 40 could be caused to move in unison by a rigid connection such as would be afforded by the 105 pin 46 shown in dotted lines in Figs. 4 and 5, and a suitable shape could then be given to the edge of the cam to afford at all times a mixture of substantially constant composition, but since it is desirable at times to vary the richness of the mixture, especially in 110 automobile work, I prefer in that case to provide separate operating connections under control of the driver, and in Fig. 6 have shown the tube arm 39 and the throttle arm 115 42 connected by rods 47, 48 to separate 120 pedals 49, 50 which may be separately actuated but are also placed so close together that they may be operated in unison by the driver's foot. The tube arm 39 is connected with a spring 51 which is strong enough to force the tube into the position shown in Fig. 2 when foot pressure is relieved. The 125 throttle arm is also provided with a returning-spring 52 and has a fixed collar 53 130 adapted to abut against a sliding stop 54 whose position may be adjusted by the operator in the usual way so as to determine the minimum opening of the throttle. Various other forms of controlling mechanism could 135

also be adopted for the purpose of independently adjusting the throttle and tube throughout their respective ranges of movement, and I do not wholly confine myself to 5 a positive or mechanical actuation of the tube by connections directly under control of the operator.

In Figs. 7 and 8 the tube cam and throttle are controlled by the driver through a 10 single operating device, and act as though rigidly connected through most of their operating range, but the tube is allowed to be further contracted after the throttle has reached its position of greatest closure. 15 is the controlling arm attached to the outer end of the rock-shaft 37 to which the cam 36 is secured as before, and 40 is the throttle-valve loosely mounted on this shaft as before, but having on the hub of its actuating 20 sleeve 43 an arm 55 between which and a shoulder 56 on the arm 39 is interposed a helical spring 57 which surrounds a curved rod 58, the latter having one end fixed by a set-screw 59 on the arm 39 and its other end 25 free to slide through an aperture in the arm 55. 60 is a stop on the hub of sleeve 43, normally held against the arm 39 by spring 57. It will be evident that when the throttle-valve 40, moving in a clockwise direction as viewed in Fig. 8, has been stopped 30 against the walls of the mixture-tube 29 while still retaining a minimum opening for the passage of mixture through the slot 41, the arm 39 may be carried slightly farther 35 in the same direction so as to decrease the size of the waist in the tube 23 and thereby provide a richer mixture for use in starting. At other times, when the throttle-valve is in a more open position, the spring 57 holds 40 the stop 60 against arm 39 and the tube and throttle are then adjusted in unison.

In practice, especially where the motor speed and load vary widely, as in automobile and to a less extent in motor-boat work, I 45 find that the most satisfactory results are obtained by adjusting the tube independently of the throttle. After once determining the proper size of the fuel-jet orifice and finding that adjustment of the air throat which 50 gives the best effect for the particular motor and under the existing atmospheric conditions, I have observed that the throat tube can be left at that adjustment through a very wide range of motor speed. This experience is contrary to accepted theories which 55 have led to the development of so-called "automatic" carburetors, which circumstance may be explainable by the fact that heretofore (so far as I am aware) no means 60 has been available for adjusting a properly-shaped Venturi or other aspirator choke-tube under running conditions to afford exactly the proper air throat for a given size of fuel orifice. The advantage of being able 65 to control the composition of the mixture by

such simple means, and the advantage of spreading the fuel into a variable air-throat which is adjustable at will under running conditions, without necessitating the employment of so-called "automatic" features, 70 will be apparent to users of this class of apparatus.

I claim,—

1. A carbureter comprising a fuel-jet nozzle, a tube composed of flexible overlapping plates adapted to form an air-throat of variable diameter around said nozzle, a mixture passage beyond said throat, controlled by a throttle-valve, and connections within the control of an operator for actuating said 75 throttle valve and adjusting said tube to vary its throat diameter, said connections adapted to permit adjustment of the tube independently of the throttle-valve.

2. A carbureter comprising a fuel-jet nozzle, a tube composed of flexible, overlapping, spring plates adapted to be bowed inwardly by axial pressure to form an air-throat of variable diameter around said nozzle, a mixture passage beyond said throat, controlled 80 by a throttle valve, a slidable ring for exerting the axial pressure, a loosely-journalized roller supported in said ring, a transverse rock-shaft crossing said passage and having an external operating member, and a cam 85 attached to said shaft and bearing against the roller.

3. A carbureter comprising a fuel-jet nozzle, a tube composed of flexible, overlapping, spring plates adapted to be bowed inwardly 100 by axial pressure to form an air-throat of variable diameter around the nozzle, a tubular casing containing the tube and forming a mixture passage beyond the same, a follower ring disconnected from the tube 105 and slidable longitudinally in said casing, and means for actuating said ring.

4. A carbureter comprising a tubular casing composed of a fixed anterior section containing a fuel-jet nozzle, a posterior section 110 detachably connected therewith, a tube mounted in said anterior section and composed of flexible, overlapping, spring plates adapted to be bowed inwardly by axial pressure and end rings in which the ends of said plates are anchored, a follower ring slidably mounted in the posterior section and abutting against the posterior end ring of the tube, and mechanism supported by said posterior section of the casing for actuating 115 said follower ring.

5. A carbureter comprising a tubular casing composed of a fixed anterior section containing a fuel-jet nozzle, a posterior section 120 rotatively adjustable on said fixed section and having means for attaching it to an engine pipe, a screw-threaded union connecting the two sections, a flexible-walled tube mounted in said anterior section and adapted to form an air-throat of variable 125

diameter around said nozzle, and means supported by the posterior section of the casing for operating said tube.

6. A carbureter comprising a fuel-jet nozzle, a tube composed of flexible, overlapping plates adapted to form an air-throat of variable diameter around said nozzle, a mixture passage beyond said throat, containing a throttle-valve, external arms for operating said tube and throttle-valve, and separate connections from said arms, within the operator's control, for independently adjusting said throttle-valve and the diameter of said throat throughout their respective ranges of adjustment.

7. A carbureter comprising a fuel-jet nozzle, a tube composed of flexible, overlapping, spring plates adapted to form an air-throat of variable diameter around said nozzle, a mixture passage beyond said throat, an oscillating throttle-valve located across said passage and having an external operating device, and an oscillating member located in said passage, co-axial with the throttle valve, and having a separate external operating device, for exerting longitudinal pressure on one end of said tube to vary the throat-diameter of the latter.

8. A carbureter comprising a tubular casing containing a fuel-jet nozzle, a tube in said casing composed of flexible, overlapping plates forming an air-throat of variable diameter around said nozzle, a mixture passage in the casing beyond said throat, a rock-shaft mounted across said passage and having an external operating arm, a butterfly throttle-valve loosely surrounding said shaft and formed with a slot, said valve having a sleeve surrounding the shaft and provided with an external operating member, and a cam attached to the shaft and occupying said slot, for exerting longitudinal pressure on one end of said tube.

9. A carbureter comprising a fuel-jet nozzle having a relatively-thin end wall formed with a discharge orifice, and a relatively-large outside diameter at its discharge end, means for causing the fuel to issue from said nozzle substantially in the form of a conical spray or film, a tube composed of flexible overlapping plates adapted to form an air-throat of variable diameter around the discharge end of said nozzle, and means for actuating said tube to vary its throat aperture.

55 10. A carbureter comprising an aspirator

having a variable air-throat formed by relatively-adjustable members, means for positively controlling the size of said throat at the will of the operator, a jet-nozzle having a relatively-small fuel orifice, and a relatively-large chamber interposed between said orifice and air-throat for permitting free expansion and vaporization of the issuing fuel spray before it encounters the air current.

11. A carbureter comprising a jet-nozzle and a surrounding air-tube forming an aspirator, said tube composed of flexible, overlapping, spring plates adapted to be more or less bowed inwardly to vary the size of the air-throat, said nozzle having a relatively-small fuel orifice and a final outlet to the aspirator of relatively-large diameter permitting the free expansion of the fuel before it encounters the air-current, and devices for throttling the mixture and for adjusting said tube to control the size of the air-throat.

12. A carbureter comprising a fuel-jet nozzle, a flexible-walled tube adapted to form an air throat of variable aperture around the outlet of said nozzle, a throttle valve interconnected with one end of said tube, and means connected with said end of the tube for adjusting the latter independently of the throttle valve.

13. In a carbureter, the combination of a fuel-jet nozzle, a flexible-walled tube forming an air throat of variable aperture about the outlet end of said nozzle, a throttle valve in the mixture passage leading from said tube, operating connections between said throttle-valve and the posterior end of the tube, and means for axially adjusting said tube by its posterior end independently of the throttle-valve.

14. In a carbureter, the combination of a mixture passage containing a throttle-valve mounted on a rock-shaft, a cam within said passage co-axial with said shaft, a fuel-jet nozzle, and a tube of variable aperture surrounding the same and composed of flexible overlapping spring blades, said tube being axially adjustable by the action of the cam.

In testimony whereof I have hereunto set my hand in the presence of two subscribing witnesses, this 8th day of December, 1913.

HERBERT H. BUFFUM.
